INVENTOR,
Harry L. Blondes,
Bates & Macklin
ATTYS.

UNITED STATES PATENT OFFICE.

HARRY L. BLONDÉS, OF CLEVELAND, OHIO.

PRINT-DEVELOPING MACHINE.

1,256,290.

Specification of Letters Patent. Patented Feb. 12, 1918.

Application filed May 14, 1917. Serial No. 168,329.

To all whom it may concern:

Be it known that I, HARRY L. BLONDÉS, a citizen of the United States, residing at Cleveland, in the county of Cuyahoga and State of Ohio, have invented a certain new and useful Improvement in Print-Developing Machines, of which the following is a full, clear, and exact description, reference being had to the accompanying drawings.

10

This invention pertains to devices for treating or developing continuous strips of sensitized paper, such as photograph or blueprint paper.

15

The essential object of this invention is to provide a simple efficient machine for treating such strips to one or more baths, then drying and ironing the same to deliver the strip in smooth dry condition and properly

20

developed so that it is no longer sensitive to light. Heretofore it has been customary to feed a strip of sensitized paper through a blueprinting machine to which a developing device is attached and through which the

25

strip is subsequently fed to bring out the print. One of the difficulties encountered in such machines is the starting of the strip through the machine which is accomplished usually by attaching the leader strip, which

30

is carefully threaded through the machine, or by feeding the end of the strip to be treated to the machine. Both of these methods are wasteful of material and time.

A more specific object of my invention is to 35 provide a machine which may coact with means attached to the end of the printed strip for causing the strip to pass entirely through the machine and permitting the printing to be begun at the foremost end of the strip.

40

The above and other objects will become apparent in the following description, which refers to the drawings, and the essential characteristics of my invention are summarized in the claims.

45

In the drawings, Figure 1 is a side elevation of my machine; Fig. 2 is a rear elevation of the same; Fig. 3 is a vertical transverse section through the machine; Fig. 4 is

50

a transverse sectional plan taken substantially on the line 4—4 of Fig. 1; Fig. 5 is an axial section through the drying and ironing drum; Fig. 6 is a perspective detail of the rear rod adapted to be attached

55

to the forward edge of the strip and cause it to progress through the machine; Fig. 7 is

a sectional side elevation of the winding mechanism.

Describing the parts by reference characters, 1 and 2 are side frame members shown 60 as made up of uprights and transverse connecting braces, illustrated at 3 and 4. The side frame members carry bearings for rollers and support the feeding liquid tanks to be described.

65

The machine is used by mounting the same adjacent a blueprinting machine adapted to progress a sensitized strip therethrough continuously and the tracings or other negatives being placed thereon and removed 70 therefrom after the printing. Such a strip is indicated at 5 as coming from the blueprint machine to a deflector or guideboard 6 from which the strip passes downwardly at 5^a into a tank 7 containing a developing 75 and fixing liquid. An associated tank 8 may contain a finishing liquid and the strip passes therethrough as indicated at 5^b and then upwardly as at 5^c to drying and ironing means to be hereinafter described. The 80 tanks 7 and 8 are shown as formed by two partially cylindrical members joined at 9 and intermediate the tank and closed at their ends by suitable end walls 10. These end walls are secured by any suitable means to 85 cross braces 11 of the frame members 1 and 2. Within the tanks 7 and 8 may be provided guide rollers 12 and 13 suspended in the tanks by depending hangers 14 and 15 loosely embracing the shafts 27 and 28. 90 These rollers are for the purpose of guiding the strip and causing it to pass through the body of liquid contained in each tank.

The strip is started through the machine by means of a clamping rod adapted to grip 95 the end of the strip. This rod may be of any suitable construction. For example, I have shown a rod somewhat oval in cross section and comprising two halves 20 and 21 hinged together at one edge by means of a hinge 100 rod 22, while projections 23 on the member 20 may pick the paper preventing it slipping therefrom. At each end of one of these members may be provided a leaf-spring 25 adapted to extend over and engage the edge 105 of the other member to hold them in engagement with the strip.

Such a leader rod may be attached to the end of the strip and strip started through the blueprint developing machine. The flatness of the rod prevents it interfering with printing close to the same and also renders

110

it easy to pass between guiding rollers and belts such as are used in blueprint developing machines. The rod is brought to the guide 6 and drops into the tank 7 and is caused to pass through the same by star-wheels 26, the projections of which engage the end of the rod. The rod reaches the roller 9^a between the tanks and falls by gravity into the path of the star-wheels and is held upwardly out of the tank 8. The star-wheels 26 and 28 are mounted rigidly on shafts 27 and 29 respectively which have their bearing boxes 30 on the cross members 11.

15 When the rod is carried upwardly by the projections of the wheels 28 it is brought into the path of hooked projections 32 on parallel chains 33 running over sprockets 34 at their lower ends and 35 at their upper ends. The sprockets 34 are mounted on a shaft 36 having bearings 37 on the cross members 16, while the sprockets 35 are rigid on a shaft 38 having a bearing 39 on upwardly extending members of the side frames. These chains are separated so that the strip may pass between them with the guiding rod having its ends engaging the hooks of the chains. As the guiding rod is brought over the tops of the sprockets 35 30 it falls downwardly onto a belt 40 running under a heating drum 42 mounted on a shaft 43 having bearings in cross members 44. At each side of the shaft 43 are rollers 45 and 46 having bearings on the member 44 and 35 on an extension 44^a, whereby the belt 40 may pass downwardly over the roller 45 beneath the drum 42 over the roller 46 and return to the roller 45. This belt has sufficient elasticity to permit the guiding rod to pass 40 between it and the drum. Upon the guiding rod passing off from the roller 46, the strip may be removed and the end of the paper started to wind on a winding roller 48 mounted in bearings on the members 44^a. 45 The heating roller is shown in detail in Fig. 5 and from this view it will be seen that the shaft 43 is made hollow and provided with radial openings 50 communicating with the interior of the drum 42, which 50 has its end walls embracing the shaft. A pipe 52 is connected through a joint 53 with a nipple 54 threaded into the shaft 43, whereby the shaft may rotate with relation to the pipe 52 by reason of the joint 53. 55 Thus hot air may be forced through the pipe 52 by any suitable means into the shaft 43 and outwardly into the drum 42, heating the latter, the air being permitted to vent through openings 55 in the end walls of the 60 drum. The strip to be treated passing between the roller and the belt is dried and ironed smooth.

If the treatment requires more than two baths of liquid an additional tank may be provided by merely extending the metal

forming the tanks 7 and 8 to provide another trough. However, ordinarily in treating blueprints to which this machine is particularly applicable only one or two kinds of treating liquid are used—usually potash 70 (in the tank 7) and water (in the tank 8). However, if a final wash is desired, such as a water wash, a tube 60 may be mounted in front of the upwardly extending strip 5^a, the tube being provided with openings to 75 project streams of water 61 onto the paper at a point where the water or other liquid will return to the tank 8. Water is led to this pipe through a tube 62 controlled by a suitable valve.

80 From the foregoing description it will be seen that my machine may be used to develop continuous strips of sensitized paper or like material whether or not it is associated with a printing machine. The machine 85 provides for using all of the strip and leads the strip through from beginning and winds the same into a roll indicated at 5^a around the shaft 48. The winding device is shown in detail in Fig. 7, and consists primarily 90 of a pulley 71 loose on the shaft 48. The pulley 71 is held against the friction disk 74 rigid on the shaft 48, by means of the spring 73, held at one end by the collar 72. The tension of this spring is adjusted to keep 95 the paper taut and as the winding roll 5^a increases in diameter the slippage between the pulley 71 and disk 74 increases in direct proportion thereto. The star-wheels 26 and 28 are preferably driven simultaneously 100 with the parallel chains 33 by means of the sprocket chain 75 and hand crank 76 mounted on the shaft 27.

The drum 42 and winding roller 48 are shown as driven by a connection with a 105 blueprinting machine as by a belt 65 leading to a pulley 66 on the shaft 43. The shafts 43 and 48 being driven by suitable belts indicated at 68 and running over pulleys 70 and 71 of these shafts 43 and 48 respectively. 110 The machine is simple, convenient and not liable to get out of order.

Having thus described my invention, what I claim is:

1. In a device for treating a flexible strip, 115 the combination of an end stiffener therefor projecting past the sides of the strip, a tank for containing treating liquid, separated rotary members engaging the stiffener to propel the strip through the tank, a winding 120 roller, and means for carrying the strip thereto.

2. A machine adapted for fixing a sensitized strip, comprising a guideway for the strip, a tank for containing said fixing liquid a stiffener on the strip, separated rotary members in said tank adapted to engage stiffener on the strip, a conveyer adapted to engage the stiffener and to cause the strip to be drawn through the liquid, and a wind- 125

ing means for continuing the progress of the strip.

3. A machine for progressively treating a continuous strip comprising separated tanks 5 for containing treating liquid, a winding means, rollers in the tanks for holding the strip in the liquid, and guide rollers between the tanks and the winding means.

4. A machine for progressively treating 10 printed sensitized strips comprising a frame, adjacent tanks for containing different treating liquids, a conveyer comprising separated flexible members, a winding means carried by the frame, a stiffener for the end of the 15 strip, separated rotary members projecting into said tanks and adapted to engage the ends of said stiffener, means for rotating said members in a direction to feed the stiffener and lead the strip therethrough.

20 5. A machine for progressively treating printed sensitized strips including adjacent tanks for containing different treating liquids, a conveyer comprising separated flexible members, a winding means, a stiffener 25 for the end of the strip, separated rotary members projecting into said tanks and adapted to engage said stiffener, means for rotating said members in a direction to feed the stiffener and lead the strip therethrough,

30 said flexible member having projections engaging the stiffener, and means for driving the conveyer and the rotary members at the same time, whereby the strip may be fed through the machine and brought to the 35 winding means.

6. The combination of a pair of adjacent tanks for containing treating liquid, said tanks being partially cylindrical, separated rotary members having outward projections, a stiffener for the end of a printed strip, means for rotating said members to cause the stiffener to pass through the tanks, a conveyer for carrying the stiffener away from the tanks, and a driving means to 45 which the conveyer delivers the strip.

7. A machine for treating continuous printed strips including tanks for containing treating liquids, a stiffener for the strip, a guideway leading to the first tank, rotary 50 members having radial projections, means carrying said rotary members so that the projections may be caused to pass the stiffener through the tanks successively, a conveyer having hooks adapted to engage the 55 stiffener and carry the strip away from the tanks, and means for winding up the strip.

8. A machine for treating continuous printed strips including tanks for treating liquids, a stiffener for containing the strip, 60 a guideway leading to the first tank, rotary members having radial projections, means carrying said rotary members so that the

projections may be caused to pass the stiffener through the tanks successively, guiding rollers beneath which the strip is passed 65 in the tanks, and a winding mechanism to which the strip is delivered.

9. The combination with adjacent tanks for containing treating liquid, guides in said tanks to lead a printed strip into the 70 liquid, means for feeding a strip with a stiffener thereon through the tanks successively, a conveyer for leading the strip away from the tanks, and manually operated means for driving the rotary members and 75 the conveyer.

10. A machine for continuously treating a blueprint strip comprising a treating tank, a guide roller therein, means for feeding the strip through the tank beneath said 80 roller, a conveyer leading the strip upwardly from the tank, a drum to which said conveyer delivers the strip, a belt beneath the drum for causing the strip to contact with the drum, a winding mechanism, said belt leading the strip to the winding mechanism, power driven means for actuating the winding mechanism, and hand operated means for actuating the feeding 85 devices and conveyer. 90

11. A machine for continuously treating a printed strip comprising a treating tank, a guide roller therein, means for feeding the strip through the tank beneath said roller, a conveyer leading the strip upwardly from 95 the tank, and a winding mechanism for the strip.

12. The combination with adjacent tanks for treating liquid, guides in said tanks to lead a printed strip into the liquid, means 100 for feeding a leading stiffener through the tanks successively, a conveyer for leading the strip away from the tanks, means for driving the rotary members and the conveyer, and a spraying tube for bringing 105 water onto the strip as it leaves the tanks.

13. In a device of the character described, the combination, with a plurality of tanks adapted to contain treating liquid, of means for guiding a strip successively through 110 such tanks, and means for winding up the strip.

14. In a device of the character described, the combination of two adjacent tanks adapted to contain treating liquid, means 115 for guiding a strip through said tanks successively, a pair of endless chains mounted side by side and constituting an elevator adapted to raise said strip from the last mentioned tank, and means for winding up 120 the dried strip.

In testimony whereof I hereunto affix my signature.

HARRY L. BLONDES.
